INVENTOR.
George C. Crossley,

BY

W. Parker Reinold:
ATTORNEY.

UNITED STATES PATENT OFFICE.

GEORGE CORLISS CROSSLEY, OF TRENTON, NEW JERSEY.

EXCAVATING AND LOADING DEVICE.

1,415,223.

Specification of Letters Patent. Patented May 9, 1922.

Application filed October 13, 1920. Serial No. 416,632.

To all whom it may concern:

Be it known that GEORGE C. CROSSLEY, a citizen of the United States, residing at Trenton, in the county of Mercer and State 5 of New Jersey, has invented certain new and useful Improvements in Excavating and Loading Devices, of which the following is a specification.

This invention relates to excavating and 10 loading machines, the primary object of which is to provide a structure of light weight and simple and inexpensive construction for facilitating the digging or scooping earth or other matter or material and transporting it any desired distance without 15 danger of tripping the conveyor or losing any of the material therefrom, and for delivering the contents of the scoop into a car, vessel, wagon or other vehicle, or for piling 20 the material at any desired place.

A further object is to provide mechanism 25 of the character and for the purpose stated which shall be of such construction as to be capable of being readily transported from place to place, and set up quickly and easily for operation; the structure when properly set up or assembled being of rigid construction and not easily broken or deranged.

A further object of the invention is to 30 provide means of this nature for greatly facilitating and expediting scooping and loading operations, which shall be used in lieu of steam shovels and other similar apparatus now generally employed for the purposes, and which may be maintained and operated at very low expense and with a minimum amount of manual labor.

With these general objects in view, together with others which will appear as the 40 description proceeds, the invention consists in the construction, combination and arrangement of parts, all as will be more fully described hereinafter, illustrated in the drawings and particularly pointed out in the 45 claims.

In the drawings:—

Fig. 1 is a side elevation of an excavating and loading mechanism constructed and arranged in accordance with the invention, the 50 view illustrating a scoop or conveyor in the act of emptying its contents into a movable receptacle,

Fig. 2 is a top plan view of the device shown in Fig. 1,

55 Fig. 3 is a top plan view of a conventional form of scoop arranged for use in connection

with the improved excavating and loading mechanism,

Fig. 4 is a side elevation of the scoop in the position it will assume when being used 60 for digging purposes,

Fig. 5 is a similar view with the scoop in position to be drawn to the elevating and dumping mechanism,

Fig. 6 is a similar view of the scoop in 65 position to be dumped, and

Fig. 7 is a detail sectional view taken through a part of the elevator device, and showing the arrangement of the cable guide rollers thereon.

70

Referring now more particularly to the drawings, an elevating structure for the traveling scoop or conveyor is indicated generally at 8. This structure includes an inclined plane 9 and a horizontal or substantially horizontal plane 10; the latter plane being disposed above the surface of the ground and communicating at one end with the upper end of the inclined plane. These planes in the present instance each comprise 80 tracks consisting of the spaced parallel rails 11, upon which the scoop or conveyor is adapted to slide. The outside longitudinal rails of each track are provided with up-standing flanges, as shown, to prevent the 85 scoop sliding off the planes. The inclined plane is disposed at such angle as to permit of the ordinary excavating scoop being slid up the same without losing therefrom any of its contents, and the horizontal plane is 90 disposed above the ground surface a distance sufficient to permit of a vehicle being positioned under one end thereof to receive the contents of the scoop when the latter is dumped. The vehicle, in the present instance, includes a railway car indicated at 12, but it will be understood that a wagon, truck or other wheeled vehicle may be used, or that the elevating device may be arranged near the bank of a canal or other body of 100 water so that the scoop may be dumped into such conveyance as may be floated beneath the dumping end of the horizontal plane.

The elevating structure is of light construction so as to permit of the same being 105 transported from place to place as required, and includes a base 13 from which the upright supports 14 extend; these supports being connected at their upper ends to the horizontal and inclined planes or trackways. 110 The outer rails of the inclined tracks are turned or flared outwardly at their lower

ends as indicated at 15, to guide an oncoming scoop onto the track properly.

The dumping or discharge end of the horizontal track or plane is provided with a 5 transversely disposed dumping roller 16, which may have its upper periphery disposed in substantially the same horizontal plane with the track 10, and upon which the loaded scoops are adapted to travel. In the 10 present instance, the said upper periphery is disposed slightly above the plane of the said track.

The scoop or conveyor is indicated at 17, and is of the usual well known type, being 15 open at its forward end and having the handles 18' at its rear end to facilitate manual operation of the scoop. The scoop is drawn forwardly onto the elevating structure by a 20 rope or cable 18, which passes over the roller 16, guide roller 19 on the supporting structure 14, and is wound upon a drum 20 driven by a suitable power plant 21. This power plant may consist of a gas or other engine arranged upon the base of the elevating 25 structure, or the cable may be drawn in any other suitable manner. The rear end of the scoop has a retracting cable 22 attached thereto for withdrawing the scoop from the elevating and dumping structure when empty, 30 and this cable extends rearwardly beyond the elevator and passes over a block or pulley 23 held by a stake or other support 24 driven into the ground. The cable 22, after passing over the block 23, passes forwardly and is 35 attached to the drum 25 operated by the power plant 21. It will be understood, of course, that when the drum 20 is operating so as to draw the scoop up the elevating structure, the drum 25 will be paying out its 40 cable 22, and the operation will be reversed when the cable 22 is being wound upon the drum 25. A horizontally disposed roller 26 is arranged near the drum 25 to support the cable 22, and this cable passes between a pair 45 of upright guide rollers 27 disposed near the ends of the said roller 26; this arrangement insuring proper passage of the cable 22 to and from the drum 25.

In order that friction in the operation of 50 the device may be reduced as much as possible, and to lengthen the life of the draft cables 18 and 22, support and guide rollers are arranged upon the structure of the elevator. A horizontally disposed supporting 55 roller 28 is mounted upon the elevator structure at the juncture of the inclined and horizontal planes thereof, and intermediate the longitudinal edges thereof. This roller is disposed below the tracks of these planes and 60 in position to support the cables 18-22, and by arranging the roller below the surface of the tracks, the scoop will be permitted to pass readily thereover without engaging the roller. Near the ends of the roller 28 and 65 arranged in spaced relation are the vertically

disposed guide rollers 29, the upper ends of which are also disposed below the tracks of the elevator so as to be free from obstructing the scoop as it travels upon the elevator. These rollers 28-29 are positioned 70 so as to receive, support and guide the cables 18-22 which control the movements of the scoop, and insure proper feeding of the same at all times.

The scoop has attached to the sides 75 thereof and preferably near the rear end of the scoop flexible members such as cables or chains 30, the forward ends of which are connected to a draft bar or yoke 31 disposed in advance of the forward end of the scoop. 80 The draft bar or yoke is connected intermediate its ends to the draft cable 18. Each side plate of the scoop is provided near its forward end with a hook member or stop 32, so positioned upon the scoop sides as to 85 overlie the members 30 when the latter are disposed parallel with the longitudinal edges of the scoop, and to be engaged by the said flexible members 30 when the rear end of the scoop is tilted upwardly. These hook or stop 90 members thus provide fulcrums for the draft chains of cables 30 when the scoop is operated for digging purposes, and forward movement of the draft cable when the scoop is tilted 95 upwardly at its rear end will cause the sharp forward end of the scoop to enter the ground.

In operation, the power plant is operated so as to retract the scoop and cause the latter to be positioned in the rear of the ground to be excavated or the matter to be moved 100 and loaded. The operator of the scoop grasps the handles 18' thereof and raises the scoop to substantially the position shown in Fig. 4 of the drawings. The power plant is then caused to operate so as to wind cable 105 18 upon the drum 20. This pull upon the cable causes the scoop to move forwardly and by reason of the point of direct pull upon the hook members 32, the forward or digging edge of the scoop will enter the ground. 110 When the scoop is filled, the operator releases the handles 18' and the scoop is drawn toward the inclined plane of the elevator, being guided thereon by the flared or outwardly turned lower ends of the outside rails 115 of the inclined track. The scoop is drawn up the inclined track and passes to the horizontal plane. Should a receiving vehicle not be positioned beneath the end of the horizontal platform 10, the scoop will be allowed 120 to rest thereon. When it is desired to dump the scoop, continued forward movement of the draft cable 18 will cause the scoop to move onto the dumping roller 16. As the scoop approaches the roller, the bail or draft bar 31 passes thereover, as does the flexible members 30; the latter passing from beneath the hook stop or fulcrum members 32. When the scoop becomes overbalanced on 125 the dumping roller, the contents thereof will 130

drop into the car or receptacle 12, and at this moment the drum 20 is halted. The power mechanism is then operated so as to unwind drum 20 and wind up the cable 22, whereupon the scoop will be caused to travel back to initial position to be again filled in the manner described. The cable 22 is at all times tensioned so as to prevent the scoop tilting too far forwardly in the dumping 5 operation. It will be understood that the tilting of the scoop on the dumping roller is slow and gradual so that the load will slowly or gradually slip therefrom and drop into the car or other vehicle, whereby wear and 10 tear on the vehicle is saved. The use of the dumping roller arranged in the manner described provides against any dead center connection between the point of pull on the draft cable and the connection of the cable with 15 the scoop.

By arranging the device in the manner shown, it is obvious that a relative large amount of dirt or material may be moved and loaded into the vehicle in a comparatively 20 short time. The stake 24 may be positioned any distance from the hoisting mechanism, and the arrangement of the cables and construction of the flared lower end of the inclined track permits of a wide range of the 25 scoop, and it is obvious that after being filled the scoop will be drawn forwardly and will be caused to be properly centered as regards the track before passing upwardly upon the same.

30 It will be understood that any preferred type of power mechanism for the device may be employed, and it will also be understood that proper clutch mechanism for the cable drums will be provided to facilitate the 40 operation. It will be further understood that the invention is not to be limited to the exact construction set forth, as variations in the mechanical structure and assemblage of parts may be resorted to if desired without 45 departing from the invention as defined by the claims.

I claim:—

1. In an excavating and loading device, 50 an inclined plane, a platform at the upper end of said plane, a cable passing over said platform and said plane, a horizontally disposed roller on said platform to support said cable, spaced vertically disposed rollers adjacent to said horizontal roller to limit the 55 lateral movement of the cable, a conveyor attached to said cable, and means for drawing said cable.

2. In an excavating and loading device, an inclined trackway, a conveyor adapted to 60 travel upon said trackway, a cable for moving said conveyor, a transverse roller between the tracks of said trackway and below the plane thereof and adapted to support said cable, and spaced upright guide rollers adjacent said transverse roller and

located wholly below the plane of the trackway.

3. In an excavating and loading device, an inclined track, a horizontal track joining the inclined track, a roller disposed 70 transversely between the rails of said track at the juncture of the inclined and horizontal tracks and wholly below the plane of the latter, upright guide rollers near the ends of said transverse roller and arranged 75 wholly below the plane of said tracks, a conveyor adapted to travel upon said tracks, and a draft cable resting upon said transverse roller and between said upright rollers and connected to said conveyor. 80

4. In an excavating and loading device, a platform, a roller on said platform, a conveyor adapted to travel upon said platform and said roller, a draft cable connected to said conveyor at a point rearwardly of the 85 forward end of the conveyor, and a stop on the conveyor in advance of said point of connection and overlying said cable.

5. In an excavating and loading device, a platform, a roller on said platform, a 90 scoop adapted to travel upon said platform and upon said roller, a draft cable connected to the sides of the scoop rearwardly of the longitudinal center of said scoop, and stops on the sides of said scoop in advance of the 95 point of connection of the cable with the scoop and overlying the cable.

6. In an excavating and loading device, a platform, a roller on said platform having its upper periphery disposed above the 100 plane of the platform, a scoop adapted to travel upon said platform and to pass onto said roller, a draft cable passing over said platform and around said roller, a bail connected to said cable, flexible members connecting the bail with the sides of the scoop 105 rearwardly of the longitudinal center of the scoop, hook members attached to the sides of the scoop near the front ends thereof and disposed above the said flexible members, 110 means for pulling said cable, and a return cable connected to the rear end of the scoop.

7. In an excavating and loading device, a platform, a roller on said platform, a conveyor adapted to travel on said platform 115 and said roller, draft apparatus disposed below said roller, and a draft cable connected to said draft apparatus at one end and attached at its other end to said conveyor at a point rearwardly of the forward end of 120 the conveyor, the said cable passing over said roller.

8. In an excavating and loading device, a platform, a roller on said platform, a conveyor adapted to travel on said platform 125 and said roller, a draft cable, a flexible bail connected to the sides of said conveyor rearwardly of the forward end thereof, the said cable being attached to said bail and passing around said roller, and stops on the sides of 130

said conveyor overlying said bail and limiting movement of the latter in upward direction.

9. In an excavating and loading device, 5 an inclined track, a platform communicating at one end with said track, a power source beyond said track and platform and below the plane of the latter, a flexible member connected to said power source at one end 10 and to the said conveyor at its opposite end, the said member being attached to said con-

veyor rearwardly of the forward end of said conveyor, the said flexible member passing upon said track and platform and downwardly below the rear edge of the latter, and 15 stops on said conveyor arranged in advance of the point of connection of the flexible member therewith and overlying said flexible member to arrest upper movement of said member upon said conveyor. 20

In testimony whereof I affix my signature.

GEORGE CORLISS CROSSLEY.
